UNITED STATES PATENT OFFICE

CHARLES DUBUQUE, OF JERSEY CITY, NEW JERSEY, ASSIGNOR TO DUBUQUE SAFETY PULLEY CORP.

SAFETY PULLEY CONSTRUCTION

Application filed October 22, 1928. Serial No. 314,144.

The present invention relates to improvements in pulleys and has for its primary object to provide means for automatically and positively gripping the rope or cable that is trained over the sheave of the pulley in case the cable accidentally breaks, thus preventing any serious injury being sustained by the workman occupying the platform that is suspended by the cable.

10 A further object is to provide a pulley of the above mentioned character which includes a vertically movable sheave that is arranged in the pulley block, resilient means being associated with the supporting means for 15 the sheave for normally urging the same upwardly, the cable that is trained over the sheave being caused to exert a downward pressure on the sheave to tension the springs when the ends of the cable are attached to a 20 platform that is to be suspended by the pulley blocks, said pulley block being formed with means at the top thereof for biting engagement with the cables in case the cable 25 breaks, said spring means automatically moving the sheave upwardly to dispose the tooth in an operative position.

A further object is to provide a pulley of the above mentioned character which is simple in construction, inexpensive, strong 30 and durable and further well adapted to the purpose for which it is designed.

Other objects and advantages of the invention will become apparent from the following description when taken in connection with the accompanying drawing.

In the accompanying drawings wherein like reference characters indicate corresponding parts throughout the same:

Figure 1 is a side elevation of a double pulley embodying my improved safety device.

Figure 2 is an end elevation thereof.

Figure 3 is an enlarged vertical sectional view through the pulley block showing the 45 mounting for the pulleys or sheaves.

Figure 4 is a vertical sectional view taken approximately on the line 4-4 of Figure 3 showing the position of the pulley wheel when the platform is properly suspended by 50 the cable trained over the pulley wheel.

Figure 5 is a similar section showing the manner in which the tooth bites into the broken cable, and

Figure 6 is a sectional view through the pulley block showing the tooth in bottom 55 plan.

In the drawings wherein for the purpose of illustration is shown the preferred embodiment of my invention, the numeral 1 designates a pulley block which in the present instance is formed with a pair of pulleys or sheave receiving openings 2 and 3, respectively, so that a double pulley will be provided. It is however, understood that a single pulley may be employed if so desired. 60 A suspension eye 4 is provided at the top of the pulley block 1. Formed at the top of each of the openings 2 and 3 and projecting downwardly therefrom is the cable engaging tooth 5 that forms a salient part of the present invention, and the purpose thereof will be presently described in detail.

The end portions of the pulley block are cut out as is also the dividing partition 6 arranged between the openings 2 and 3, and this 75 arrangement is more clearly disclosed in Figure 3 of the drawings.

A pair of plates 7 and 8 are arranged in spaced relation within each of the cut out portions formed in the ends and intermediate portion of the pulley blocks and each of said plates is provided with a central longitudinally extending slot 9. All of these slots are disposed in communication with each other as also clearly illustrated in Figure 3. The 80 slotted plates that are associated with the intermediate portion 6 of the pulley block are denoted by the reference characters 10 and 11.

A pair of horizontally disposed pins 12 90 and 13, respectively are arranged for vertical slidable movement within the openings 2 and 3, respectively, and upon referring to Figure 3, it will be noted that the pin 12 projects through the slotted plates at the 95 left hand side of the block 1, and the inner end of this pin extends into the openings formed in the intermediate portion 6 that is disposed through the slot formed in the plate 10. The other pin 13 extends through the 100

other pair of apertured plates 7 and 8, and the inner end of this pin projects through the slot formed in the plate 11 for disposition within the opening formed in the intermediate partition 6.

5 A sheave or pulley wheel 14 is mounted for rotation on the intermediate portion of the pin 12 and is arranged within the opening 2, a similar sheave 15 being supported on the 10 intermediate portion of the other pin 13 for disposition within the opening 3. The scaffold supporting cables are trained over the respective pulleys or sheaves as indicated by the dotted lines in Figure 1, and also in Figures 3 and 4, the free ends of the cables being 15 attached to the scaffolds or platform in the usual manner.

The invention further comprehends the provision of vertically disposed rods 16 that are arranged within the openings formed in 20 the ends of the intermediate portion of the pulley block 1 and one of such rods is located within each of the end openings for disposition between the spaced plates 7 and 8, while two of these rods are positioned between the 25 plates 10 and 11. The upper ends of these rods extend through the respective ends of the respective shafts and are formed at their upper ends with heads 17, while the lower ends of these rods are arranged for vertical 30 movement within the sockets 18 formed in the lower portion of the pulley block 1 and which sockets extend downwardly from the lower or bottom sides of the respective end or intermediate openings formed in the pulley 35 block.

An expandible coil spring 19 encircles the intermediate portion of each rod and is disposed between the bottom of the respective opening in the pulley block, and the respective ends of said shaft for normally urging the shaft and the pulley wheels supported thereon in an upward direction.

Additional coil springs 20 are provided 45 for effecting the upward movement of the pulley supporting shaft. These coil springs 20 are connected at their lower ends to the respective heads 17, while the upper ends of the springs 20 are secured to the eyed lower 50 ends of suitable pins 22 that project upwardly into the top portion of the pulley block 1 as clearly indicated in Figure 3. The lower coil springs 19 are expandible to exert an upward sliding movement of the shaft 55 in the slots 9 while the upper coil springs are retractile springs to assist in moving the shaft and the sheaves supported thereon in an upward direction.

The weight of the scaffold or platform 60 supported by the cables A exerts a pressure on the shafts to move the same downwardly in the respective slots 9, and the tooth 5 in each of the cut out portions 2 and 3 will be disposed out of engagement with its respective cables.

However, should either of the cables accidentally break, the springs 19 and 20 will automatically move the shaft 12 or the shaft 13 depending upon which of the cables has been broken upwardly, so that the broken cable will be forced against the tooth 5 and this tooth will cooperate with the sheave and the springs to support the scaffold or platform in such a manner as to enable the workman to safely leave the scaffold or permit 75 him to repair the broken cable.

As heretofore mentioned, this safety device may be used with a single pulley as well as with a multiple pulley structure, and the safety mechanism will at all times be positive and efficient as well as automatic in its 80 operation.

Furthermore, the parts of the safety mechanism are so arranged as not to interfere with the ordinary use of the pulley, and the parts are so assembled as to enable ready access thereto whenever necessary.

While I have shown the preferred embodiment of my invention it is to be understood that minor changes in the size, shape and arrangement of parts may be resorted to without departing from the spirit of the invention and the scope of the appended claims.

Having thus described the invention, what I claim as new and desire to secure by Letters Patent is:—

1. In combination with a pulley block, a sheave yieldingly mounted therein, automatic means for normally urging the sheave upwardly in the pulley block, said means being disposed in an inoperative position when a downward pull is exerted on a cable trained over the sheave, and means for gripping the cable when the same accidentally breaks as in the manner described.

2. In combination with a pulley block, a sheave yieldingly mounted therein, automatic means for normally urging the sheave upwardly in the pulley block, said means being disposed in an inoperative position when a downward pull is exerted on a cable trained over the sheave, means for gripping the cable when the same accidentally breaks as in the manner described, said means comprising a downwardly projecting tooth arranged in the top of the pulley block for disposition above the sheave.

3. In combination, a pulley block formed with a central opening, a transverse shaft extending through the opening, the opposite sides of the pulley block being formed with slots to accommodate the ends of the shaft and in which said shaft is arranged for vertical slidable movement, a sheave supported for rotation in the intermediate portion of the shaft for disposition within the opening in the pulley block, a cable gripping tooth extending downwardly from the top of the opening and normally maintained out of engagement with the cable trained over the

sheave, said cable normally exerting a downward pressure on the shaft to hold the same in its lowered position in the opening, and spring means associated with the ends of the shaft for automatically moving the shaft and sheave upwardly when the cable is broken to effect the biting engagement of the tooth with the broken cable in the manner as described.

10 4. In combination, a pulley block formed with a central opening, a transverse shaft extending through the opening, the opposite sides of the pulley block being formed with slots to accommodate the ends of the shaft and in which said shaft is arranged for vertical slidable movement, a sheave supported for rotation in the intermediate portion of the shaft for disposition within the opening in the pulley block, a cable gripping tooth extending downwardly from the top of the opening and normally maintained out of engagement with the cable trained over the sheave, said cable normally exerting a downward pressure on the shaft to hold the same in its lowered position in the opening, and spring means associated with the ends of the shaft for automatically moving the shaft and sheave upwardly when the cable is broken to effect the biting engagement of the tooth with the broken cable in the manner as described, said spring means comprising vertically disposed sliding pins or rods arranged in the side portions of the pulley block, the upper ends of the rods being connected to the respective ends of the shaft, the lower ends of the rods being operable within sockets formed in the bottom portion of the pulley block, 65

20 5. In combination, a pulley block formed with a central opening, a transverse shaft extending through the opening, the opposite sides of the pulley block being formed with slots to accommodate the ends of the shaft and in which said shaft is arranged for vertical slidable movement, a sheave supported for rotation in the intermediate portion of the shaft for disposition within the opening in the pulley block, a cable gripping tooth extending downwardly from the top of the opening and normally maintained out of engagement with the cable trained over the sheave, said cable normally exerting a downward pressure on the shaft to hold the same in its lowered position in the opening, and spring means associated with the ends of the shaft for automatically moving the shaft and sheave upwardly when the cable is broken to effect the biting engagement of the tooth with the broken cable in the manner as described, said spring means comprising vertically disposed sliding pins or rods arranged in the side portions of the pulley block, the upper ends of the rods being connected to the respective ends of the shaft, the lower ends of the rods being operable within sockets formed in the bottom portion of the pulley block, and expandible coil springs encircling

the rods for disposition between the sockets and the respective ends of the shaft.

6. In combination, a pulley block formed with a central opening, a transverse shaft extending through the opening, the opposite sides of the pulley block being formed with slots to accommodate the ends of the shaft and in which said shaft is arranged for vertical slidable movement, a sheave supported for rotation in the intermediate portion of the shaft for disposition within the opening in the pulley block, a cable gripping tooth extending downwardly from the top of the opening and normally maintained out of engagement with the cable trained over the sheave, said cable normally exerting a downward pressure on the shaft to hold the same in its lowered position in the opening, and spring means associated with the ends of the shaft for automatically moving the shaft and sheave upwardly when the cable is broken to effect the biting engagement of the tooth with the broken cable in the manner as described, said spring means comprising vertically disposed sliding pins or rods arranged in the side portions of the pulley block, the upper ends of the rods being connected to the respective ends of the shaft, the lower ends of the rods being operable within sockets formed in the bottom portion of the pulley block, 95 expandible coil springs encircling the rods for disposition between the sockets and the respective ends of the shaft, the upper ends of the rods projecting through the respective ends of the shaft, and retractile coil springs 100 connected at their lower ends to the upper projecting ends of the respective rods and at their upper ends to the top portion of the pulley block.

In testimony whereof I affix my signature. 105
CHARLES DUBUQUE.
